(57) **CLAIM**

The ornamental design for a step fairing for motor vehicle, as shown and described.

DESCRIPTION

FIG. 1 is a perspective view of a step fairing for a motor vehicle according to a second embodiment of our new design; FIG. 2 is a front elevational view of the step fairing for a motor vehicle of FIG. 1;

FIG. 3 is a top plan view of the step fairing for a motor vehicle of FIG. 1;

FIG. 4 is a bottom plan view of the step fairing for a motor vehicle of FIG. 1;

FIG. 5 is a right side elevational view of the step fairing for a motor vehicle of FIG. 1; and,

FIG. 6 is a left side elevational view of the step fairing for a motor vehicle of FIG. 1.

FIGS. 1-6 illustrate a first embodiment of our novel design suitable for use on the right side of a vehicle. Our novel design also includes a second embodiment suitable for use on the left side of a vehicle, which is mirrored symmetrical to FIGS. 1-6 and therefore not separately illustrated.

The broken lines shown in the drawings illustrate portions of the step fairing for motor vehicle that form no part of the claimed design.
